UNITED STATES PATENT OFFICE.

THOMAS C. McBRIDE, OF PHILADELPHIA, PENNSYLVANIA.

SURFACE CONDENSER.

1,311,239.

Specification of Letters Patent. Patented July 29, 1919.

Application filed May 1, 1918. Serial No. 94,577.

To all whom it may concern:

Be it known that I, THOMAS C. McBRIDE, a citizen of the United States, residing in the city and county of Philadelphia, State of Pennsylvania, have invented a new and useful Surface Condenser, of which the following is a specification.

My invention consists of a novel surface condenser in which the cooling water is passed through the tubes in a novel manner, thereby effecting not only a reduction in the amount of cooling water required but also a reduction in the power to pump it.

It is a well known fact that but very little heat is taken up by the cooling water which passes through the tubes in proximity to the outlet opening which is connected to the air pump. This water and the power necessary to pump it are therefore largely wasted.

This is due to the fact that the air and noncondensable vapors entering and passing through the condenser with the steam, while they form an extremely small proportion of the immense volume of steam as it enters the condenser, are a very appreciable portion of the volume of steam that is left still uncon- densed at and near the outlet to the air pump. This large proportion of air mixed with the steam not only lowers its tempera- ture but also acts as does air alone, and re- quires much greater surface to transmit the same amount of heat than is required by steam.

As the process above described is gradual and progressive, the steam proportion must be the least and the air proportion the greatest at the outlet opening to the air pump and the condenser tubes located at this point will take up the least amount of heat of any in the condenser and therefore will be of low- est efficiency. Furthermore, the tubes must become more and more efficient with in- creased distance from the outlet opening to the air pump, measured backward along the steam path through the condenser owing to the increase of the proportion of steam to air. The function of the tubes nearest the outlet opening to the air pump is therefore principally that of cooling air, while in the balance of the condenser, the function of the tubes is that of condensing steam.

A partition is frequently used in surface condensers in order to give the steam and air approaching the opening to the air pump a little more definite direction and a longer path between the tubes and this partition

and the tubes inclosed within it are called the cooler.

It will be apparent, however, that this cooler partition while it changes the steam path through the condenser as to direction or length or both, does not in any way modify the above action. In this descrip- tion therefore the word cooler is used not only to indicate this space partially partitioned off from the balance of the condenser and the tubes within it but also the tubes surround- ing the outlet opening to the air pump where no partition is used, the function of these tubes being that of cooling air more than that of condensing steam.

The waste of cooling water and the power necessary to pump it is most serious in single pass condensers wherein the water enters one end of the condenser, passes through all the tubes of the condenser and leaves at the other end of the condenser. It is also a fac- tor in two-pass condensers where the water first passes through one half, generally the bottom half of the tubes, then turns back and passes in the opposite direction through the other half of the tubes, in spite of the fact that the second pass furnishes a second op- portunity for any water to take up heat which has failed to be taken up in going through any of the tubes in the first pass.

With the above conditions in view, it is the object of my present invention to eliminate this waste of water and power by so group- ing the tubes that the water in those in proximity to the outlet opening to the air pump or in and near the cooler will pass back and forth through the condenser a greater number of times than the water in the condenser proper.

My invention consists of a novel construc- tion and arrangement of a surface condenser with a cooler having a plurality of passes, some of the passes having a greater number of tubes than the other passes and preferably having the greatest number of tubes in the first pass with a decreasing number of tubes in the succeeding passes.

It further consists of a novel construction and arrangement of tubes and a novel con- struction and arrangement of partitions and baffles, whereby the requisite results are obtained.

Other novel features of construction and advantage will hereinafter more clearly ap- 110- pear in the detailed description of my inven- tion.

For the purpose of illustrating my invention, I have shown in the accompanying drawing a typical embodiment which will illustrate the principles of the invention and which in practice will give satisfactory and reliable results, although it is of course to be understood that the various instrumentalities of which my invention consists can be variously arranged and organized and that 10 my invention is not limited to the precise arrangement and organization of these instrumentalities as herein described.

Figure 1 represents a vertical section on line 1—1 of Fig. 2, of a surface condenser or 15 cooler embodying my invention.

Fig. 2 represents a horizontal section on line 2—2 of Fig. 1.

Fig. 3 represents a sectional view of another embodiment of my invention.

20 Similar numerals of reference indicate corresponding parts in the figures.

Referring to the drawings:

For convenience of description, the portion of condenser and tube surface surrounding 25 the opening from the condenser to the air pump suction may be called the cooler whether it is partially inclosed in a partition or not, as its function is to cool the air and uncondensable vapors before they leave the 30 condenser.

It is desirable to place the first pass of 35 the cooler whose tubes carry the coolest water next to the outlet to the air pump with successive passes arranged in order, so that the final pass will be next to or part of 40 the condenser itself. Under these conditions, the first pass of the cooler because of its location will receive the least heat per unit surface and the succeeding passes more and more heat.

In my present invention, therefore, the first pass has the greatest number of tubes and the succeeding passes a decreasing number of tubes, thus causing a lower water velocity and a decreased friction loss in the 45 first pass with increased velocity within the succeeding passes. By this arrangement, advantage is taken of the fact that the power of the water side of the tube surface to 50 transmit heat increases with the increase of the velocity of the water in the tubes and an endeavor is made to so proportion the number of the tubes in the several passes, that the heat transmitting power of the water 55 side of the tube surface will always be equal to or slightly greater than that of the steam side of the tube surface at all points throughout the cooler, thus keeping the water velocity down to the lowest point possible 60 without reducing the heat transferring power of the tube surface, and likewise reducing the power necessary for pumping the water.

1 designates a condenser embodying my invention and provided with a steam inlet 2 65 at its top and with a port 3 which is in com-

munication with the air pump in any desired or conventional manner. 4 designates the hot well at the bottom, the function of which is to collect the water of condensation.

5 designates a longitudinally extending 70 baffle which inclines downwardly from the side wall of the condenser above the port 3 and terminates in a downward extension 6. 7 designates a cooler having the passes 8, 9 and 10. This divides the tubes in the cooler 75 into three sections, the pass 8 having the greatest number of tubes, the pass 9 an intermediate number and the pass 10 the smallest number of tubes. 11 designates the main 80 pass of the condenser.

The cooling water enters through the water inlet 12 into the water chamber 13 and passes through the tubes in the main pass 11 to the water chamber 14 at the opposite end of the condenser and thence through 85 the outlet 15 to the waste or to a desired point of utilization. A portion of the cooling water passes from the water chamber 13 through the tubes in the pass 8, therefrom into the chamber 16 formed by the partition 90 17. This cooling water then passes from the chamber 16 through the tubes in the pass 9 and therefrom into the chamber 18 formed by the plate 19 and thence through the tubes in the pass 10 to the water chamber 95 14 and the outlet 15. The water is thus directed back and forth through the cooler by appropriate partitions in the two water chambers at the ends of the condenser.

In the form illustrated, which is a single-pass condenser, the water passes through the main condenser but once, and the water going through the cooler passes back and forth three times, thus having an ample opportunity to take up its full quota of heat 100 before going to waste in spite of the low heat transmitting power of the tube surface in the cooler, because of the great proportion of air mixed with the steam surrounding these tubes.

110 It is also within the scope of my invention to apply the principle here involved to a two-pass condenser by using a three-pass cooler in the bottom half, the water from which joins the water from the bottom half and passes with it to and through the top half. It is advisable in some cases to make the major part of the condenser two-pass and the balance four-pass, which latter may have the first two of the four passes in the 115 cooler with the other two passes outside. The first of the four passes because of its having the coldest water, would be in front of the opening to the air pump suction and the next pass between this and the entrance 120 to the cooler. The third and fourth passes may be in the condenser.

125 It is desirable in some cases to make one of the passes of the cooler a return pipe instead of a bank of tubes, or instead of the 130

last pass, to carry the water leaving next to the last pass directly off to the waste through a separate opening from the proper water chamber of the condenser. Thus, a 5 single pass condenser might have a two-pass cooler, the condenser having but one water inlet but two water outlets, one from the condenser itself and the other from the cooler or it might have independent water 10 inlets for the condenser and for the cooler, and a common outlet for both. Furthermore, the water connections to or from the condenser or cooler might have valves in them so that the amount of water passing 15 through the condenser or cooler could be varied or regulated.

It is also within the scope of my invention to place gates or valves 20 and 21 respectively, see Fig. 2, in the partitions in the 20 water boxes, so that the number of passes in the cooler can be modified, or by partly opening these gates or valves, the relative amount of water passing through the condenser and the several passes of the cooler 25 may be varied as desired. Thus, in a single pass condenser and a three-pass cooler, the opening of these valves will change the cooler to a single pass like the condenser, and this condition is sometimes desirable 30 to meet excessive overload with a reduced vacuum, especially if an additional circulating water pump is available. It might also be desired to so arrange these valves that the cooler could be run with less passes in 35 the summer than in the winter time.

It will be apparent that I provide an unequal number of tubes in the different passes of the cooler and preferably have the pass 40 having the greatest number of tubes in proximity to the opening leading to the air pump. In the embodiment illustrated, I form a single pass surface condenser with a multi-pass cooler. In certain cases it is advantageous to have some of the passes outside 45 of the cooler proper as seen in Fig. 3.

It will now be apparent that I have devised a new and useful construction of a surface condenser which embodies the features of advantage enumerated as desirable in the 50 statement of the invention and the above description, and while I have, in the present instance, shown and described preferred embodiments thereof which will give in practice satisfactory and reliable results, it is 55 to be understood that the same are susceptible of modification in various particulars without departing from the spirit or scope of the invention or sacrificing any of its advantages.

Having thus described my invention, what 60 I claim as new and desire to secure by Letters Patent, is:—

1. A surface condenser or cooler, provided with means to cause the cooling water to separate and a portion of it to pass a greater 65 number of times through the tubes in that part of the condenser in the neighborhood of the outlet opening from the condenser to the air pump than in the balance of the condenser, there being an unequal number 70 of tubes in the several sections or passes in the neighborhood of the outlet opening from the condenser to the air pump.

2. A surface condenser or cooler, provided with means to cause the cooling water to 75 separate and a portion of it to pass a greater number of times through the tubes in that part of the condenser in the neighborhood of the outlet opening from the condenser to the air pump than in the balance of the condenser, there being an unequal number of 80 tubes in the several sections or passes in the neighborhood of the outlet opening from the condenser to the air pump, and the first section immediately at the outlet opening 85 from the condenser to the air pump having the greatest number of tubes.

3. A condenser with one part having a greater number of passes than the other, the cooling water passing separately through 90 such two parts, some of the passes of the former part being arranged in front of the outlet opening from the condenser to the air pump, and the pass nearest the outlet opening containing the largest number of 95 tubes.

4. A surface condenser or cooler, provided with means to cause the cooling water to separate and a portion of it to pass a greater 100 number of times through the tubes in that part of the condenser in the neighborhood of the outlet opening from the condenser to the air pump than in the balance of the condenser, the water in the first part first passing through the tubes right in front of 105 the outlet opening from the condenser to the air pump, partitions in said means provided with ports, and valves controlling said ports.

5. A single pass surface condenser, with a 110 multi-pass cooler, there being an unequal number of tubes in the different passes of the cooler, and a single source of supply for said condenser and cooler.
